US00D942017S

(12) **United States Design Patent** (10) **Patent No.:** **US D942,017 S**
(45) **Date of Patent:** **** Jan. 25, 2022**

(54) **PROTECTIVE VACUUM SHIELD FOR PERSONAL SERVICE PROVIDERS**

(71) Applicants: **David J. Ahearn**, Little Compton, RI (US); **Edward Carey**, Westport, MA (US); **Walter Bezaniuk**, Berkley, MA (US)

(72) Inventors: **David J. Ahearn**, Little Compton, RI (US); **Edward Carey**, Westport, MA (US); **Walter Bezaniuk**, Berkley, MA (US)

(**) Term: **15 Years**

(21) Appl. No.: **29/737,787**

(22) Filed: **Jun. 11, 2020**

(51) LOC (13) Cl. **24-02**

(52) U.S. Cl.

USPC **D24/184**

(58) **Field of Classification Search**

CLAIM

The ornamental design for a protective vacuum shield for personal service providers, as shown and described.

DESCRIPTION

FIG. 1 is a perspective view of a protective vacuum shield for personal service providers according to our new design; FIG. 2 is a front view thereof;

FIG. 3 is a back view thereof;

FIG. 4 is a side view thereof;

FIG. 5 is an opposite side view thereof;

FIG. 6 is a top view thereof;

FIG. 7 is a bottom view thereof;

FIG. 8 is another perspective view of the protective vacuum shield for personal service providers in use; and,

FIG. 9 is another perspective view of the protective vacuum shield for personal service providers in use.

The broken lines in the drawings depict environmental subject matter and form no part of the claimed design.

1 Claim, 7 Drawing Sheets
